(57) **CLAIM**

The ornamental design for LED beacon for walking cane, as shown and described.

DESCRIPTION

FIG. 1 is a front view of custom LED beacon for walking cane, showing our new design.

FIG. 2 is a left view thereof.

FIG. 3 is a bottom view thereof.

FIG. 4 is a rear view thereof.

FIG. 5 is a top side view thereof.

FIG. 6 is a right planar view thereof.

FIG. 7 is a bottom front right perspective view thereof.

FIG. 8 is a front bottom, left perspective view thereof.

FIG. 9 is a top, front right perspective view thereof.

FIG. 10 is a top front, left perspective view thereof; and, FIG. 11 is a bottom front right perspective view thereof as in use on a cane.

The broken lines in the drawings depict portions of the LED beacon for walking cane and form no part of the claimed design. The additional broken lines shown in FIG. 11 depict background and form no part of the claimed design.

1 Claim, 6 Drawing Sheets
